No. 725,992.

PATENTED APR. 21, 1903.

W. ROCHE,
ELECTRIC LIGHTER.
APPLICATION FILED APR. 18, 1902.

NO MODEL.

UNITED STATES PATENT OFFICE.

WILLIAM ROCHE, OF JERSEY CITY, NEW JERSEY.

ELECTRIC LIGHTER.

SPECIFICATION forming part of Letters Patent No. 725,992, dated April 21, 1903.

Application filed April 18, 1902. Serial No. 103,539. (No model.)

To all whom it may concern:

Be it known that I, WILLIAM ROCHE, a citizen of the United States, residing at Jersey City, county of Hudson, State of New Jersey, have invented certain new and useful Improvements in Electric Lighters, of which the following is a specification.

My invention relates to electric lighters of that class in which an inflammable fluid is caused to be ignited by the action of electricity, and is particularly applicable for the purpose of lighting cigars.

The object of my invention is to provide a simple and efficient device of the above-indicated class which will operate without the use of a spark-coil and which will utilize the same part which holds the inflammable liquid as the igniter proper.

To this end my invention consists in certain features of construction and combinations of parts, as will be particularly pointed out in the appended claims.

In the accompanying drawings I have shown two forms of my invention as examples.

Figure 1 is a sectional elevation of an electric lighter constructed according to my invention. Fig. 2 is a detail showing the construction of the lighter proper. Fig. 3 is a diagram of the circuit. Fig. 4 shows the second form of my invention, and Fig. 5 is a detail of another form of my invention.

As illustrated in Figs. 1, 2, and 3, the apparatus comprises a battery, preferably consisting of a series of cells A, which may be located within a case B, these cells being connected with each other in series or in any other suitable way. On the outside of the case, preferably on the top thereof, there is a contact C, connected with one end of the battery. The case also contains a receptacle D, preferably arranged in the center, this receptacle being adapted to contain a readily inflammable liquid, such as alcohol. Into the top of the receptacle fits the lower end of a handle E, which thus forms a stopper to prevent undue evaporation of the liquid. This handle is made of insulating material and has two rods F G projected therefrom downwardly, one of said rods or wires F being longer than the other, which is connected with the other pole of the battery, as by a

wire H. Around the rod G is coiled a wire I of relatively considerable thickness, and with this coil is connected a transverse coil J, the other end of which is secured to the long rod or wire F.

The two coils I J normally dip into the liquid, such as alcohol, contained in the receptacle D, so that upon withdrawing the handle a suitable amount of liquid will be carried by the said coils. As the coil J extends transversely, so as to lie practically horizontal, there is little danger of the liquid dropping off. The apparatus is used by touching the end of the rod F against the contact C, whereupon the circuit will be closed through the coil J, which being of relatively small thickness and preferably of a material which is a bad conductor of electricity, such as platinum, will become heated sufficiently to ignite the alcohol carried by said coil J and also by the coil I. The purpose of the coil I is to hold an additional amount of alcohol; but it will be understood that it may be sufficient to use the coil J only. (See Fig. 5.) The rod F is made longer, so that the end of the other rod G may not accidentally be brought against the contact C.

While I have referred to the handle as made of insulating material, it is of course not absolutely necessary that the entire handle should consist of such material; but all that is required is that the connection from one rod F to the other rod G, or rather to the wire H, should be entirely through the coil J. In order to prevent the handle from being separated too far from the case B, I may attach a flexible connection, such as a string or a chain K, to the case and to the handle E.

In the form of construction shown in Fig. 4 I have done away with the necessity of always lighting the alcohol at the same place and have shown a construction by which the handle of the igniter may be carried to any desired place and the alcohol lighted wherever desired. For this purpose instead of connecting one end of the battery with a stationary contact-plate I connect it with one of the rods F' G', which form the terminals for the coil J', and the other pole of the battery I connect by a wire H' with a switch L, operated by a push-button L' to establish contact

between the wire H' and the other terminal F' or G'. Thus all the user has to do after withdrawing the handle from the alcohol-receptacle is to press the push-button L' whenever the igniter has been carried to the desired spot.

I desire to again emphasize that the two constructions hereinbefore described are only examples of the various modes of carrying out my invention.

What I claim as new, and desire to secure by Letters Patent, is—

1. An electric lighter, comprising a receptacle adapted to contain a liquid fuel, a handle provided with a coil arranged to dip into said liquid and disposed transversely so that it will normally be in a horizontal position, said coil being adapted to become heated upon the passage of an electric current, and means for passing an electric current through said coil.

2. An electric lighter comprising a receptacle adapted to contain a liquid fuel, a handle provided with two conducting members projecting therefrom longitudinally, a fuel-carrying coil connecting said members transversely, and means for passing an electric current through said coil.

3. An electric lighter comprising a receptacle adapted to contain a liquid fuel, a handle provided with two longitudinally-extending conducting members, one of which projects beyond the other, a transverse coil connecting said members and adapted to dip into the liquid fuel, and means for passing an electric current through said coil.

4. An electric lighter comprising a receptacle adapted to contain a liquid fuel, a handle provided with two members projecting therefrom longitudinally, a longitudinal coil surrounding one of said members, a fuel carrying and lighting coil extending transversely between said members, and means for passing an electric current through said lighting-coil.

5. An electric lighter comprising a receptacle adapted to contain a liquid fuel, a handle provided with a transverse lighting-coil adapted to dip into the fuel, a longitudinal coil adjacent to said lighting-coil, and means for passing an electric current through the lighting-coil.

WILLIAM ROCHE.
